UNITED STATES PATENT OFFICE.

MARTIN B. MATTSON, OF PRINCETON, MINNESOTA.

BOG-SHOE.

1,237,077.

Specification of Letters Patent. Patented Aug. 14, 1917.

Application filed November 11, 1916. Serial No. 130,829.

To all whom it may concern:

Be it known that I, MARTIN B. MATTSON, a citizen of the United States, residing at Princeton, in the county of Millelacs and 5 State of Minnesota, have invented new and useful Improvements in Bog-Shoes, of which the following is a specification.

This invention relates to bog shoes for horses or similar draft animals and it consists in the novel features hereinafter described and claimed.

An object of the invention is to provide a bog shoe such as may be applied to the shoe of a horse when the animal is used 15 upon soft or marshy ground and a further object of the invention is to provide such a shoe which may be easily and quickly adjusted to fit the foot of the animal.

With this object in view the shoe comprises a board having means for retaining 20 the rear portion of the shoe which is permanently fixed to the hoof of the animal and means adapted to be passed over the upper forward portion of the hoof whereby 25 the board is held in position below the permanent shoe.

In the accompanying drawing:—

Figure 1 is a side elevation of one form 30 of the shoe showing the same applied.

Fig. 2 is a top plan view of the form of shoe shown in Fig. 1.

The shoe includes a board 1 which is preferably of wood or other suitable light material. A lug 2 is mounted upon the upper 35 surface of the board 1 in the vicinity of one side edge thereof and a similar lug 3 is mounted in the vicinity of the opposite side edge of the said board. The said lugs 2 and 3 are provided with a series of perforations 4 which are adjusted to receive bolts 5 whereby metallic strips 6 are adjustably connected with the said lugs. The bolt 7 passes transversely through the free end 40 portions of the strips 6 and is adapted to secure the free end of the strips together over the upper forward portion of the animal. The board 1 is provided at that side portion upon which the lug 3 is mounted with a series of perforations 8 adapted to 45 receive the bolt 9 which secures the lug 3 to the board. Thus it is possible to shift the lug 3 transversely of the board 1. The lug 2 is secured to the board 1 by means of a bolt similar to the bolt 9 hereinbefore 50 described. These bolts pass transversely through the board 1 and through a metallic 55

strip 10 which is positioned against the lower side of the board 1. The board 1 is provided at its upper side and in the vicinity of its rear edge with a transversely disposed channel 11 which receives the body portion of a bar 12. The said bar 12 is provided at one end with an upstanding lug 13 which is disposed at an acute angle with relation to the median longitudinal dimension of the bar 12 and which is adapted to bear against the outer side of one heel portion of the permanent shoe of the animal. The bar 12 is provided in the vicinity of that end opposite the end at which the lug 13 is located with a series of perforations 14. The board 1 is provided at the forward edge of the channel 11 and near the perforations 14 with a recess 15 which enters the said channel 11. A bolt 16 passes through one 60 of the perforations 14 and transversely through the board 1 and also passes through the base portion 17 of a lug 18 which is adjustably mounted upon the bar 12. The lug 18 is disposed at an acute angle with 65 relation to the median longitudinal dimension of the bar 12 and is adapted to bear against the outer edge portion of one heel portion of the permanent shoe of the animal.

The base portion 17 is provided with a 70 downwardly disposed flange 19 which is received in the recess 15. Therefore it will be seen that means are provided for shifting the base 17 with relation to the lug 13 and the flange 19 prevents the lug 18 from 75 turning after it has been fixed at an adjusted position under the bar 12. A bolt 20 passes transversely through the bar 12 and also the board 1 and the bolts 16 and 20 pass transversely through a strip 21 80 which is positioned against the underside of the board 1. The strips 10 and 21 are disposed transversely of the grain of the board and prevent the same from splitting when the device is in use.

The lugs 3 and 18 are adjusted transversely of the board 1 to fit the foot or hoof of the animal and when the heel portions of the permanent shoe are positioned between the lugs 13 and 18 the strips 16 are extended 90 over the upper forward portion of the hoof and secured by the bolts 7 whereby the board 1 is securely held in position upon the hoof of the animal. When this form of the invention is employed the permanent 105 shoe of the animal is devoid of heel and toe carks and when the device is applied the 110

animal may move freely and without effort over soft or marshy ground.

Having described the invention what is claimed is:

- 5 A bog shoe comprising a board, means for connecting the board with the forward portion of the hoof of an animal, said board being provided in the vicinity of its rear edge with a transversely disposed channel, 10 the board having at the forward edge of the channel and in the vicinity of one end a recess which communicates with the channel, a bar located in the channel and having

at one end an upstanding lug, said bar being provided in the vicinity of its other end 15 with a series of perforations, a base member mounted upon the bar, a bolt passing through the base member and one of the perforations, said base member having an upstanding lug, the base member being further provided with a flange which bears 20 against the edge of the bar and lies in the said recess.

In testimony whereof I affix my signature.

MARTIN B. MATTSON.
